DESIGN FOR A GAME BOARD

Ronald O. Dock, Minneapolis, Minn.

Application December 18, 1946, Serial No. 135,586

Term of patent 3½ years

(Cl. D34—5)

To all whom it may concern:

Be it known that I, Ronald O. Dock, a citizen of the United States, residing at Minneapolis, in the county of Hennepin and State of Minnesota, have invented a new, original, and ornamental Design for a Game Board, of which the following is a specification, reference being had to the accompanying drawing, forming part thereof.

Fig. 1 is a top plan view of a game board showing my new design;

Fig. 2 is a side elevational view, partially in section, illustrative of any one of the sides of the game board; and

Fig. 3 is a bottom plan view on a reduced scale, I claim;

The ornamental design for a game board, as shown and described.

RONALD O. DOCK.
